THERAPEUTIC SUSPENSIONS OF STEROIDS CONTAINING PVP AND/OR PVA

Jack K. Dale, Kalamazoo, and Samuel L. Ross, Kalamazoo Township, Kalamazoo County, Mich., assignors to The Upjohn Company, Kalamazoo, Mich., a corporation of Michigan

No Drawing, Application May 4, 1954
Serial No. 427,678

9 Claims. (Cl. 167—65)

This invention relates to new compositions of matter containing steroids and to a process for the preparation thereof. More particularly, it relates to compositions containing an insoluble steroid in combination with one or more hydrophilic polyvinyl compounds, said combinations being either in the form of an aqueous suspension suitable for therapeutic use or in the form of a dry admixture which is suitable for the extemporaneous preparation of an aqueous fluid. The invention also relates to a process for inhibiting crystal growth of steroids.

The preparation of stable aqueous suspensions of insoluble steroids has presented considerable difficulties. For example, aqueous suspensions of crystalline cortisone acetate, progesterone, testosterone propionate, estradiol monobenzoate, and the like, are characterized by crystal growth. This is a real problem since large crystals can be a source of great irritation to patients, can cause mechanical difficulties in attempting to pass large crystals through fine hypodermic needles, and have a considerable effect upon the suspendability of the active material. So little is known about the mechanism of crystal growth, that it is almost impossible to predict what materials or methods will retard it.

It is an object of the invention to provide novel compositions of matter containing insoluble steroids which are suitable for therapeutic use. Another object of the invention is to provide stable aqueous suspensions of steroids suitable for therapeutic use which will remain relatively free of crystal growth, even after extended periods of time. Another object of the invention is to provide dry therapeutic compositions containing a steroid which will readily form a stable suspension on the addition of an aqueous vehicle without being subject to excessive crystal growth. Other objects are to provide novel procedures for preparing such compositions and novel ways of inhibiting the crystallization of steroids. Still other objects of the invention will be apparent to those skilled in the art to which this invention pertains.

The invention provides compositions of matter containing a hydrophilic polyvinyl compound such as polyvinyl pyrrolidone, polyvinyl alcohol, or the like, and mixtures thereof, in combination with a steroid such as cortisone acetate, progesterone, testosterone propionate, estradiol monobenzoate, or the like, said compositions being either in the form of an aqueous suspension or in the form of a dry admixture readily dispersible to form the same. These suspensions are characterized by the absence of excessive crystal growth.

The marked superiority of the hydrophilic polyvinyl compounds of the invention as crystal growth retardants for therapeutic steroid compositions as compared with other suspending agents is clearly evident from the data set forth in the following tables. Thus, steroid suspensions prepared according to the invention are characterized by the absence of undue crystal growth in suspension even after storage for extended periods of time at room temperature.

The following tables compare the effect of two hydrophilic polyvinyl compounds with other suspending agents on the crystal growth of a steroid, illustratively, cortisone acetate and cortisone acetate hydrate, the comparisons being made after storage at room temperature.

2

for the various times indicated. Table I illustrates the effect of the hydrophilic polyvinyl compounds on the crystal growth of cortisone acetate as compared with other suspending agents. The cortisone acetate is in aqueous suspension in the concentration of fifteen milligrams per cubic centimeter with 0.1 percent weight by volume of the suspending agent.

TABLE I

10 The effect of various suspending agents on the crystal growth of cortisone acetate in suspension

Suspensing Agent	Crystal Size			
	Initial	4 days	3 wks.	2 mos.
15 Polyvinyl Alcohol	<10 μ	<10 μ	<10 μ	<10 μ
Polyvinyl Pyrrolidone	<10 μ	<10 μ	<10 μ	<10 μ
Acacia U. S. P.	<10 μ	100%>10 μ	—	—
Dextran	<10 μ	50%>10 μ	—	—
Sodium Carboxymethylcellulose	<10 μ	20%>10 μ	—	—
20 Pectin N. F.	<10 μ	80%>10 μ	—	—
Sodium Alginate	<10 μ	60%>10 μ	—	—

From the data given in Table I it will be seen that only polyvinyl alcohol and polyvinyl pyrrolidone effectively inhibited the crystal growth of cortisone acetate.

25 Table II illustrates the effect of the hydrophilic polyvinyl compounds on the crystal growth of cortisone acetate hydrate as compared with other suspending agents. Each suspension contained fifteen milligrams per cubic centimeter of cortisone acetate hydrate, 0.1 percent suspending agent and 0.02 percent "Quatresin" (myristyl gamma picolinium chloride) as a preservative.

TABLE II

The effect of various suspending agents on the crystal growth of cortisone acetate in aqueous suspension

Suspensing Agent	Crystal Size			
	Initial	4 days	3 wks.	2 mos.
40 Polyvinyl Alcohol	<10 μ	<10 μ	<10 μ	<10 μ
Polyvinyl Pyrrolidone	<10 μ	<10 μ	<10 μ	10%>10 μ
Acacia U. S. P.	<10 μ	100%>10 μ	—	—
Dextran	<10 μ	100%>10 μ	—	—
Sodium Carboxymethylcellulose	<10 μ	40%>10 μ	—	—
45 Pectin N. F.	<10 μ	80%>10 μ	—	—
Sodium Alginate	<10 μ	10%>10 μ	—	—

50 The data given in Table II shows that only polyvinyl alcohol and polyvinyl pyrrolidone of the suspending agents tested inhibit growth of cortisone acetate hydrate.

55 Table III illustrates various preservatives which can be substituted for "Quatresin" and the effect of the preservatives on the crystal growth of cortisone acetate hydrate in aqueous suspensions. No suspending agent was used.

TABLE III

The effect of various preservatives on the crystal growth of cortisone acetate in aqueous suspension

Preservative	Crystal Size			
	Initial	1 day	2 wks.	2 mos.
60 0.02% "Quatresin" (myristyl gamma picolinium chloride)	<10 μ	1%>10 μ	1%>10 μ	100%>10 μ
65 0.01% "Methylate" (sodium ethylmercurithiosalicylate)	<10 μ	<10 μ	1%>10 μ	100%>10 μ
0.5% Chlorobutanol	<10 μ	<10 μ	1%>10 μ	100%>10 μ
0.5% Benzyl Alcohol	<10 μ	10%>10 μ	—	100%>10 μ
1.5% Benzyl Alcohol	<10 μ	100%>10 μ	—	100%>10 μ
0.5% Phenol	<10 μ	100%>10 μ	—	100%>10 μ
0.1% Methylparaben	<10 μ	1%>10 μ	1%>10 μ	100%>10 μ
70 Deionized water (control)	<10 μ	0.1%>10 μ	—	100%>10 μ

The data given in Table III shows that neither "Quatresin" nor any of the other preservatives tested have any apparent inhibitory effect on the crystal growth of cortisone acetate hydrate in aqueous suspension.

The following table illustrates the crystal growth in aqueous suspensions of cortisone acetate hydrate (at a concentration of fifteen mgs./cc.) containing various suspending agents after storage at room temperature for various periods of time and the re-suspendibility of these suspensions after an extended period of time. In all instances, 0.1 percent weight by volume of the suspending agent is used.

TABLE IV

Suspending Agent	Re-suspendibility		Crystal Growth	
	Initial, Shakes	10 mos., Shakes	Initial	3 wks.
Polyvinyl Alcohol	3-10	13-----	<10 μ	*<10 μ
Polyvinyl Pyrrolidone	3	1-2-----	<10 μ	*<10 μ
Acacia U. S. P.	3-10	3-10-----	<10 μ	50%, 20-100 μ
Dextran	1-2	dried up-----	<10 μ	60%, 20-80 μ
Sodium Carboxymethylcellulose	1-2	20 (clumped)-----	<10 μ	100%, 10-40 μ
Pectin N. F.	1-2	20 (clumped)-----	<10 μ	20%>10 μ
Methylcellulose	1-2	20 (clumped)-----	<10 μ	20%>10 μ
Sodium Alginate	1-2	1-2-----	<10 μ	100%, 20-60 μ

*No crystal growth after ten months.

Since the clumps obtained in the three instances noted above could not be broken up, suspensions of this type are unsatisfactory for ophthalmic use or injection and are generally unsuitable for therapeutic use because of lack of uniformity in dosage.

Of the suspending agents tested, only the aqueous suspensions of cortisone acetate hydrate containing polyvinyl alcohol and polyvinyl pyrrolidone were both readily re-suspendible and free of crystal growth. These suspensions are therapeutically useful, especially for ophthalmic use or parenteral injection.

Table V illustrates the effect of suspending agents set forth in Table I and "Quatresin," on crystal growth in aqueous suspensions of cortisone acetate hydrate (at a concentration of fifteen mgs./cc.) after storage at room temperature for various periods of time and also the re-suspendibility of these suspensions after an extended period of time. In all instances, 0.02 percent "Quatresin" and 0.1 percent suspending agent, weight by volume, are used.

TABLE V

"Quatresin" + Suspending Agent	Re-suspendibility		Crystal Growth	
	Initial, Shakes	10 mos., Shakes	Initial	3 wks.
Polyvinyl Alcohol	3-10	3-10-----	<10 μ	<10 μ
Polyvinyl Pyrrolidone	3-10	3-10-----	<10 μ	1%>10 μ
Acacia U. S. P.	>10 (caked)	>20 (caked)-----	<10 μ	100%, 20-80 μ
Dextran	>10 (caked)	>20 (caked)-----	<10 μ	100%, 10-70 μ
Sodium Carboxymethylcellulose	1-2	>20 (caked)-----	<10 μ	100%, 20-80 μ
Pectin N. F.	1-2	>20 (caked)-----	<10 μ	100%, 20-60 μ
Methylcellulose	1-2	>20 (caked)-----	<10 μ	20%, 10 μ
Sodium Alginate	1-2	1-2-----	<10 μ	100%, 20-60 μ
Control—only 0.02% "Quatresin"	1-2	1-2-----	<10 μ	20%>10 μ

In combination with "Quatresin," only the aqueous suspensions of cortisone acetate hydrate containing polyvinyl alcohol and polyvinyl pyrrolidone were readily re-suspendible and free of crystal growth.

The cortisone acetate hydrate used herein is conveniently prepared by dissolving cortisone acetate in a water-methanol mixture (e. g., 100 grams of cortisone acetate is dissolved in a mixture of 250 milliliters of water and 25 liters of methanol), filtering the mixture to remove impurities, allowing the filtrate to crystallize and carefully drying the crystals to obtain cortisone acetate in its hydrated form.

The polyvinyl hydrophilic compounds of the inven-

tion are of pharmaceutical grade, non-toxic, inert and capable of being sterilized without change in composition. On the addition of water to a dry composition containing a steroid and the selected hydrophilic polyvinyl compound, followed by mixing, a stable steroid suspension is readily obtained.

The polyvinyl pyrrolidone used in the compositions described herein is sold by the General Aniline and Film Company under the trademark "Plasdone" and is characterized by a viscosity coefficient, i. e., K value, of 26 to 36 and a molecular weight of about 40,000. However, it is to be understood that the invention is not to be limited to the use of this specific polyvinyl pyrrolidone since other equivalent polyvinyl pyrrolidones of pharmaceutical grade are likewise suitable. While a polyvinyl pyrrolidone of pharmaceutical grade possessing a molecular weight between twenty and eighty thousand is preferred, satisfactory results are also obtained by the use of a polyvinyl pyrrolidone outside of this molecular weight range.

The polyvinyl alcohol utilized in the compositions described herein is sold by the DuPont Company under the trademark "Elvanol" 51-05 and is characterized by a viscosity of four to six centipoises (four percent aqueous solution at twenty degrees centigrade), a pH of six to eight and a 86 to 89 percent hydrolysis from polyvinyl acetate. It is to be understood, however, that the invention is not limited to the use of this specific polyvinyl alcohol since any other equivalent polyvinyl alcohol of pharmaceutical grade can likewise be used to achieve similar results.

The amount of hydrophilic polyvinyl compound which can be used in the compositions of the invention can vary from a range of 0.01 percent weight by volume up to ten percent weight by volume. However, the preferred range of concentration is between 0.1 to five percent weight by volume. The preferred range varies with the type of preparation however. For example, for an eye preparation, a concentration of about 0.1 to about 0.4 percent weight by volume is preferred. Higher concentrations make eyelids sticky. For injection use concentrations of one to two percent are preferred to keep the suspension from darkening.

The compositions of the present invention are especially suitable for therapeutic application either parenterally, orally, or topically. For example, sterile aqueous suspensions of cortisone acetate, cortisone acetate hydrate, and the like, are especially useful as topical ophthalmic

applications. Ophthalmic preparations of this nature are not perceptible in the eye and are non-irritating. For oral use, cortisone acetate, progesterone, and the like, are especially suitable.

Furthermore, other therapeutic materials can be incorporated with the compositions containing the selected hydrophilic polyvinyl compound and steroid to form new and extremely valuable compositions. Such therapeutic materials include antibiotics such as neomycin, penicillins such as penicillin G, penicillin O, procaine penicillin, and the like, bacitracin, chloramphenicol, streptomycin, dihydrostreptomycin, erythromycin, oxytetracycline, chlortetracycline, tetracycline, polymyxin, circulin, endomycin,

and the like, or mixtures of these antibiotics. It should be noted that the importance of combinations of an antibiotic with a steroid such as, for example, neomycin and cortisone, neomycin and hydrocortisone, neomycin and esters of these steroids, and the like, has not been fully appreciated hitherto since these combinations possess valuable therapeutic properties which are not solely attributable to the individual members of these combinations. For example, while combinations of neomycin and cortisone acetate have been prepared in the form of ointments, creams, jellies, powders, and the like, suspensions of these materials are particularly valuable for therapeutic use such as, for example, topically, ophthalmic application, oral administration, aerosols for the relief of respiratory difficulties, and the like. The 9α -halo derivatives of the indicated steroids can be substituted therefor in the preparations shown and described. By the addition of the selected hydrophilic polyvinyl compound to an aqueous suspension of an antibiotic such as neomycin, and a steroid such as cortisone acetate, and the like, the stability imparted to these compositions greatly enhances their value.

A typical composition of the invention in the form of an aqueous suspension is prepared by providing a vehicle usually containing a hydrophilic polyvinyl suspending agent, a preservative to insure a sterile product, a lubricant (where ophthalmic use is contemplated), a buffer to maintain the pH of the suspension between 6.5 and 8.0 and an isotonic agent to adjust the osmotic pressure approximately equivalent to 0.9 percent saline. Conventional preservatives, buffers, isotonic agents, and lubricants (glycerol, sorbitol, and the like), can be used. Suitable preservatives include 0.01 percent "Merthiolate," 0.5 percent chlorobutanol, 0.02 percent "Quatresin" and 0.1 percent methylparaben. Non-toxic wetting agents such as "Tween-80" (polyoxyethylene sorbitan monoleate), "Quatresin," and the like, are included in the suspensions because their characteristic wetting action on crystals aids re-suspension after storage. The vehicle is adjusted to a pH between 6.5 and 8.0, deionized water added to the desired volume and the mixture is then filter sterilized by passing through a Hormann filter. The sterilized vehicle is combined aseptically with the desired sterilized steroid, the resulting composition passed through a sterile colloid mill and then bottled and sealed. In preparing a suspension of a steroid such as progesterone, cortisone acetate, or the like, the steroid is micronized or otherwise prepared in the desired particle size, sterilized, for example, by exposure to ethylene oxide vapor, and then combined with a suitable vehicle to form a suspension. Particle size of the steroid is significant since coarse particles will not pass through a hypodermic needle and in the case of an ophthalmic preparation, may cause irritation of the eye. It has been found that proper particle size is achieved in an oral preparation when the majority of the particles of the composition are within the range of about five to eighty microns, and for parenteral or ophthalmic use, preferably fifteen microns or less in size.

Thus, in the preparation of a typical composition of the invention, between 0.01 percent and ten percent of the selected hydrophilic polyvinyl compound which has been dried and sterilized is mixed with at least 0.02 percent of a sterilized and dried steroid which is subject to crystal growth. The composition can exist in the form of a dried admixture for the extemporaneous preparation of an aqueous fluid. In the dry form, the product is very stable and can be stored for relatively long periods of time. To use the dry composition, an indicated amount of sterile water, sterile saline solution and other ingredients novel to the composition of this type are added, followed by mixture or agitation.

The following examples are illustrative of the compositions of this invention together with the procedure for the preparation thereof but are not to be construed in any way as limiting the invention thereto.

EXAMPLE 1

A vehicle containing the following ingredients:

		Grams
5	Polyvinyl pyrrolidone	50
	d-Sorbitol-crystalline	25
	"Quatresin"	0.2
10	Sodium citrate	1
	Sodium chloride	4
	N/10 NaOH solution in sufficient quantity to adjust pH between 6.8 and 7.5, q. s.	
	Deionized water, q. s. 1000 cc.	

is mixed and filter sterilized. The vehicle is then combined aseptically with 25 grams of cortisone acetate hydrate which has been sterilized and micronized to a particle size of less than ten microns. The mixture is passed through a sterile colloid mill, bottled and sealed. The final product is a sterile suspension of a pH between 6.8 and 7.5 and a freezing point depression of about 0.54 degrees centigrade. After storage for an extended period of time, 98 percent of the particles are less than ten microns while the remaining two percent are less than forty microns.

EXAMPLE 2

A vehicle containing the following ingredients:

		Grams
	Polyvinyl pyrrolidone	20
30	Sodium chloride	9
	"Quatresin"	0.2
	N/10 NaOH to adjust pH between 7.0 and 7.5, q. s.	
	Deionized water, q. s., 1000 cc.	

is mixed and filter sterilized. The vehicle is then combined aseptically with 25 grams of progesterone which has been sterilized and micronized to a particle size of less than ten microns. The mixture is passed through a sterile colloid mill, bottled and sealed. The sterile suspension thus obtained has a pH between 7 and 7.5, is isotonic and can pass through a 26 (or finer) gauge hypodermic needle. There is no evidence of growth in particle size in this suspension even after storage for a 17 month period.

EXAMPLE 3

45 Following the procedure described in Example 2 except for the substitution of progesterone by testosterone propionate, a sterile, stable suspension of testosterone propionate is obtained which is suitable for therapeutic use. There is no evidence of growth in particle size in 50 this suspension even after storage for 17 months.

EXAMPLE 4

A vehicle containing the following ingredients:

		Grams
55	Polyvinyl pyrrolidone	1
	Dextrose	25
	Neomycin sulfate	6
60	Sodium citrate	4.5
	"Quatresin"	0.2
	Deionized water, q.s. 1000 cc.	

is mixed and filter sterilized. The vehicle is then combined aseptically with 25 grams of cortisone acetate hydrate which has been sterilized and micronized to a particle size of less than ten microns. The mixture is passed through a sterile colloid mill, bottled and sealed. The final product is a sterile suspension of a pH between 7 and 7.5 and a freezing point depression of about 0.54 degree centigrade. The suspension separates slightly 65 on standing but re-suspends easily on inverting the container. The product is useful as an ophthalmic preparation. After storage for an extended period of time, there is no evidence of growth in particle size.

75 The use of neomycin sulfate in Example 4 is illustrative only since other neomycin derivatives can also

be used such as, for example, neomycin base, neomycin hydrochloride, neomycin citrate, and the like, to achieve similar results.

Similarly, other antibiotics such as bacitracin, chloramphenicol, erythromycin, penicillins such as penicillin O, penicillin G, procaine penicillin, and the like, oxytetracycline, chlortetracycline, tetracycline, circulin, endomycin, streptomycin, dihydrostreptomycin, polymyxin, and the like, can also be used to form compositions, either in dry form or in suspension, suitable for therapeutic use.

EXAMPLE 5

A vehicle containing the following ingredients:

	Grams
Polyvinyl alcohol	4
Soluble saccharin	1
Sucrose	700
Benzoic acid	1
Methylparaben	1
Deionized water, q. s., 1000 cc.	20

is mixed. To the resulting solution is added fifty grams of cocoa, five grams of micronized progesterone (particle size less than ten microns) and 0.1 cubic centimeter of imitation black walnut flavor. The product contains particles less than ten microns in size and is characterized by a pleasant chocolate-nut flavor making it especially suitable for oral use.

EXAMPLE 6

A vehicle containing the following ingredients:

	Grams
Polyvinyl pyrrolidone	20
Sodium chloride	9
"Quatresin"	0.2
N/10 NaOH to adjust pH between 7.0 and 7.5, q. s.	35
Deionized water, q. s., 1000 cc.	

is mixed and filter sterilized. The vehicle is then combined aseptically with 25 grams of cortisone acetate hydrate which has been sterilized and micronized to a particle size of less than ten microns. The mixture is passed through a sterile colloid mill, bottled and sealed. The sterile suspension thus obtained has a pH between 7 and 7.5, is isotonic and can pass through a 26 gauge (or finer) hypodermic needle.

EXAMPLE 7

Following the procedure described in Example 6 except for the substitution of cortisone acetate hydrate by hydrocortisone acetate, a sterile suspension of hydrocortisone acetate is obtained which is suitable for therapeutic use. There is no evidence of growth in particle size in this suspension even after storage for a prolonged period of time.

EXAMPLE 8

A vehicle containing the following ingredients:

	Grams
Polyvinyl pyrrolidone	1
d-Sorbitol-crystalline	25
"Quatresin"	0.2
Sodium citrate	1
Sodium chloride	4
N/10 NaOH solution in sufficient quantity to adjust pH between 6.8 and 7.5, q. s.	
Deionized water, q. s., 1000 cc.	

is mixed and filter sterilized. The vehicle is then combined aseptically with 25 grams of estradiol monobenzoate which has been sterilized and micronized to a particle size of less than ten microns. The mixture is then passed through a sterile colloid mill, bottled and sealed. The final product is a sterile suspension with a pH between 6.8 and 7.5.

EXAMPLE 9

A vehicle containing the following ingredients:

	Grams
5 Polyvinyl alcohol	4
Soluble saccharin	1
Sucrose	700
Benzoic acid	1
Methylparaben	1
10 Deionized water, q. s., 1000 cc.	

is mixed. To the resulting mixture is added fifty grams of cocoa, five grams of micronized cortisone acetate (particle size less than ten microns) and 0.1 cubic centimeter of imitation black walnut flavor. The product contains particles less than ten microns in size and is especially suitable for oral use.

EXAMPLE 10

A vehicle containing the following ingredients:

	Grams
Polyvinyl pyrrolidone	1
Dextrose	25
Neomycin sulfate	6
Sodium citrate	4.5
"Quatresin"	0.2
Deionized water, q. s., 1000 cc.	

is mixed and filter sterilized. The vehicle is then combined aseptically with 25 grams of estradiol monobenzoate which has been sterilized and micronized to a particle size of less than ten microns. The mixture is passed through a sterile colloid mill, bottled and sealed. The final product is a sterile suspension of a pH between 7 and 7.5. The product is useful for topical application. After storage for an extended period of time, the suspension is free of crystal growth.

The use of neomycin sulfate in this example is illustrative only since other neomycin derivatives can also be used such as, for example, neomycin base, neomycin hydrochloride, neomycin citrate, and the like, to achieve similar results.

Similarly, other antibiotics such as bacitracin, chloramphenicol, erythromycin, penicillins such as penicillin O, penicillin G, procaine penicillin, and the like, oxytetracycline, chlortetracycline, tetracycline, circulin, endomycin, streptomycin, dihydrostreptomycin, polymyxin, and the like, can also be used to form compositions, either in dry form or in suspension, suitable for therapeutic use.

EXAMPLE 11

A vehicle containing the following ingredients:

	Grams
55 Polyvinyl pyrrolidone	25
Sodium citrate	1
"Merthiolate"	0.1
"Quatresin"	0.2
Chlorobutanol	5
Sodium chloride	9
60 Deionized water, q. s., 1000 cc.	

is mixed and filter sterilized. The vehicle is then combined aseptically with 25 grams of cortisone acetate which has been sterilized and micronized to a particle size of less than ten microns. The mixture is passed through a sterile colloid mill, bottled and sealed. The final product is a sterile suspension of a pH between 7 and 7.5 and a freezing point depression of 0.66 degree Centigrade. Crystal growth is greatly retarded after storage for a prolonged period of time.

EXAMPLE 12

Following the procedure described in Example 11 except for the inclusion in the vehicle of six grams of neomycin sulfate, a sterile, stable suspension of neomycin

and cortisone acetate suitable for therapeutic use is obtained.

EXAMPLE 13

The following ingredients:

Polyvinyl alcohol	mg	25
Polyvinyl pyrrolidone	mg	25
Crystalline d-sorbitol	mg	250
Bacitracin	units	1000
"Quatresin"	mg	1
Cortisone acetate	mg	75

are intimately combined in the form of a fine powder (or suitably milled together) and placed in a vial. On adding five cubic centimeters of water and shaking for fifteen to thirty seconds, a non-irritating suspension results which is suitable for use as a nosedrop preparation even after storage for prolonged periods of time.

It is to be understood that the invention is not to be limited to the exact details of operation or exact compositions shown and described herein as obvious modifications and equivalents will be apparent to one skilled in the art. The invention is therefore to be limited only by the scope of the appended claims.

We claim:

1. An aqueous therapeutic suspension comprising a water-insoluble steroid subject to crystal growth and from 0.01 to ten percent weight by volume of a member selected from the group consisting of polyvinyl pyrrolidone, polyvinyl alcohol, and a mixture thereof.

2. An aqueous therapeutic suspension comprising a water-insoluble steroid subject to crystal growth, an antibiotic, and from 0.01 to ten percent weight by volume of a member selected from the group consisting of polyvinyl pyrrolidone, polyvinyl alcohol, and a mixture thereof.

3. A dry therapeutic composition suitable for the extemporaneous preparation of an aqueous suspension comprising a water-insoluble steroid subject to crystal growth and from 0.01 to ten percent weight by volume of a member selected from the group consisting of polyvinyl pyrrolidone, polyvinyl alcohol, and a mixture thereof.

4. A dry therapeutic composition suitable for the extemporaneous preparation of an aqueous suspension comprising a water-insoluble steroid subject to crystal growth, an antibiotic, and from 0.01 to ten percent weight by volume of a member selected from the group consisting

of polyvinyl pyrrolidone, polyvinyl alcohol, and a mixture thereof.

5. An aqueous therapeutic suspension comprising a steroid selected from the group consisting of cortisone acetate, hydrocortisone acetate, estradiol monobenzoate, testosterone propionate, and progesterone and from 0.01 to ten percent weight by volume of a member selected from the group consisting of polyvinyl pyrrolidone, polyvinyl alcohol, and a mixture thereof.

6. An aqueous therapeutic suspension comprising cortisone acetate and from 0.01 to ten percent weight by volume of a member selected from the group consisting of polyvinyl pyrrolidone, polyvinyl alcohol and mixtures thereof.

15 7. An aqueous therapeutic suspension comprising cortisone acetate hydrate and from 0.01 to ten percent weight by volume of a member selected from the group consisting of polyvinyl pyrrolidone, polyvinyl alcohol and mixtures thereof.

8. An aqueous therapeutic suspension comprising cortisone acetate, an antibiotic and from 0.01 to ten percent weight by volume of polyvinyl pyrrolidone.

9. An aqueous therapeutic suspension comprising cortisone acetate hydrate, neomycin sulfate, and from 0.01 to ten percent weight by volume of polyvinyl pyrrolidone.
